US0D1013501S

(12) **United States Design Patent** (10) **Patent No.:** **US D1,013,501 S**
Sharrah et al. (45) **Date of Patent:** **** Feb. 6, 2024**

(54) **CLAMPING MEMBERS**

(71) Applicant: **STREAMLIGHT, INC.**, Eagleville, PA (US)

(72) Inventors: **Raymond L Sharrah**, Collegeville, PA (US); **William D. Worman**, Phoenixville, PA (US)

(73) Assignee: **Streamlight, Inc.**, Eagleville, PA (US)

(**) Term: **15 Years**

(21) Appl. No.: **29/885,515**

(22) Filed: **Feb. 24, 2023**

Related U.S. Application Data

(62) Division of application No. 29/745,707, filed on Aug. 7, 2020.

(57) **CLAIM**

The ornamental design for clamping members, substantially as shown and described.

DESCRIPTION

FIG. 1 is a perspective view of an ornamental design of clamping members;

FIG. 2 is a perspective view thereof in the environment of a light;

FIG. 3 is a perspective view thereof from an opposite side than FIG. 1;

FIG. 4 is a view of a first side of the clamping members;

FIG. 5 is a view of a first end thereof;

FIG. 6 is a view of a second end thereof;

FIG. 7 is a view of a third side thereof; and,

FIG. 8 is a view of a fourth side thereof.

Broken lines in the drawing indicate parts of the article that are not claimed herein, or its environment in FIG. 2 that is not claimed herein, and that form no part of the claimed design.

1 Claim, 4 Drawing Sheets
